CIRCUIT BREAKER CONTROL SYSTEM

Hans Thommen, Baden, Switzerland, assignor to
 Aktiengesellschaft Brown Boveri & Cie, Baden,
 Switzerland, a joint-stock company

Application January 7, 1939, Serial No. 249,687
 In Germany January 14, 1938

9 Claims. (Cl. 175—294)

This invention relates in general to improvements in circuit breaker control systems, and more particularly to a control system for a circuit breaker comprising arcing contacts which are immediately reclosed upon opening thereof and disconnecting contacts which are opened only upon repeated operation of the arcing contacts.

It is frequently desired to control a circuit breaker in such manner that the circuit breaker contacts reclose immediately upon interrupting operation thereof, the contacts thereafter reopening and remaining open if the operating condition causing the first opening of the contacts is still present. It is, however, desirable to shorten as much as possible the time required for the entire sequence of operations of the circuit breaker to reduce the disturbing effects of such operations on the performance of electric motors and other apparatus connected with the circuit controlled by the circuit breaker. To obtain such result the circuit breaker preferably comprises fluid actuated arcing contacts which are light in weight and which travel only a short distance while being swept by a blast of fluid to momentarily interrupt the flow of current therethrough. The circuit breaker is also provided with disconnecting contacts which are suitably interlocked with the arcing contacts to open only during a predetermined time interval following at least one reclosing and reopening of the arcing contacts and to thereafter maintain the circuit open.

If the circuit breaker is of large dimensions, the arcing contacts are preferably provided with fluid actuated reclosing means operable while the contact opening means are still acting to reduce the time required for reclosing and reopening the arcing contacts. If the circuit to be controlled is a polyphase circuit the different pole portions of the circuit breaker may be actuated independently of one another in dependence upon the occurrence of disturbances in the circuit conductors associated therewith, but it is generally preferable to cause all pole portions of the circuit breaker to function simultaneously to avoid continued operation of the circuit as a single phase circuit.

It is therefore one of the objects of the present invention to provide a control system for a circuit breaker operable to control positively the opening and closing operations of the arcing contacts of the circuit breaker and to cause the disconnecting contacts of the circuit breaker to be opened upon reopening of the arcing contacts.

Another object of the present invention is to

provide a control system for a multipole circuit breaker operable to cause the disconnecting contacts of all pole portions of the circuit breaker to be opened upon repeated opening of the circuit breaker arcing contacts.

Another object of the present invention is to provide a control system for a circuit breaker for causing the arcing contacts of the circuit breaker to be opened by fluid under pressure and to be reclosed while the contact opening operation is continued.

Objects and advantages other than those above set forth will be apparent from the following description when read in connection with the accompanying drawings, in which:

Fig. 1 diagrammatically illustrates one embodiment of the present invention in which the operation of the disconnecting contacts is controlled through a pneumatic relay responsive to reclosure of the arcing contacts;

Fig. 2 diagrammatically illustrates a modified embodiment of the present invention in which the operation of the disconnecting contacts is controlled through an electromagnetic relay;

Fig. 3 is a diagram of the connections of the circuit breaker contacts in a polyphase electric circuit;

Fig. 4 is a chart of the operation of the embodiment illustrated in Fig. 1; and

Fig. 5 is a chart of the operation of the embodiment illustrated in Fig. 2.

Referring more particularly to the drawings by characters of reference, reference numeral 6 generally designates a circuit breaker of the fluid actuated type comprising cooperating arcing contacts 7, 8 serially connected with cooperating disconnecting contacts 9, 10 in an electric circuit 11. Circuit breaker 6 may be of the single pole type, as illustrated in Fig. 1 to simplify the drawing, but if circuit 11 is a polyphase circuit, circuit breaker 6 will comprise a plurality of pole portions equal in number to the number of phase conductors of circuit 11 as illustrated in Fig. 3. The different pole portions may be independently controlled, but it is generally preferable to jointly control all the pole portions to avoid continued operation of circuit 11 as a single phase circuit upon opening of less than all the pole portions of circuit breaker 6.

Circuit breaker 6 comprises a reservoir 12 serving as a source of supply of fluid under pressure and preferably also serving as support for the circuit breaker contacts. The fluid utilized for actuation of the circuit breaker is assumed to be compressed air supplied to reservoir 12 and main-

tained therein at a substantially constant pressure by a suitable compressor (not shown) but it will be understood that other fluids such as nitrogen or helium may also be utilized. Reservoir 12 supports three insulators 13, 14, 16 of dimensions which are determined by the voltage of circuit 11. Insulators 13 and 16 are fixed and support the fixed disconnecting contacts 10 of the circuit breaker. Insulator 14 carrying the movable disconnecting contact 9 of the circuit breaker is pivotally mounted on reservoir 12 and may be rotated by suitable contact separating means such as an air motor 17 of any suitable known type to cause opening of the disconnecting contacts. The disconnecting contacts may be closed by another air motor 18.

Insulator 16 is hollow and defines part of the arcing chamber 19 of the circuit breaker which is further defined by another hollow insulator 21 supported on insulator 16 in alignment therewith and by a cap member 22 containing the operating mechanism for contact 7. The arcing chamber is provided with an inlet valve 23 for controlling the admission of air under pressure from reservoir 12 into the arcing chamber and to the separating means for contacts 7, 8. Valve 23 may be opened by means of a compressed air motor 24 acting against a spring 25. Contact 7 is hollow and is provided with a spring 26 continuously tending to maintain contacts 7 and 8 closed. The contacts are provided with fluid actuated contact separating means such as a piston 27 adapted to be displaced in a cylindrical chamber of cap 22 also serving for the passage of the air discharged from the arcing chamber through contact 7. Air under pressure may be admitted under the lower face of piston 27 from arcing chamber 19 through a check valve 28 and through a pneumatically actuatable slide valve 29. Piston 27 also controls the admission of air under pressure under the lower face of an annular slide valve 31 having a cylindrical portion adapted to abut against a plate 32 to close the passage for the flow of air issuing from the bore of contact 7.

Opening operation of circuit breaker 6 is controlled in response to an operating condition of circuit 11 such as the magnitude of the flow of current therethrough by means of a current transformer 33 connected in circuit 11 and supplying current to the coil of a relay 34. Relay 34 controls the connection of a suitable auxiliary current source such as a battery 36 with the coil 37 of a magnet valve 38 through an auxiliary switch 39 mounted on the shaft of contact 9. Valve 38 connects motor 24 with atmosphere when the valve coil is deenergized and connects motor 24 with reservoir 12 to cause opening of valve 23 and opening of contact 7 when the valve coil is energized.

Another magnet valve 41 having a coil 42 is arranged similarly to valve 38 to supply air under pressure from reservoir 12 to the left side of a piston 43 slidable in the cylindrical bore of an air relay 44. A second piston 45 of relay 44 controls the supply of air from arcing chamber 19 to motor 17. A third piston 46 mounted on the shaft of pistons 43 and 45 controls the supply of air from reservoir 12 through valve 23 and arcing chamber 19 to the space below slide valve 29 to control reopening of contact 7. Piston 43 is also operable to close a plurality of contacts 47 controlling the energization of coils 37 and 42. A push button switch 48 is connected across those contacts 47 which control coil 42.

The connection between arcing chamber 19 and slide valve 29 includes a reservoir 49 serving as a time delay device and a pressure actuated valve 51 having a relatively small piston 52 operable to open the valve for causing reclosure 5 of contact 7. Valve 51 is provided with a relatively large second piston 53 operable to reclose the valve under the control of valve 41. Air is admitted through valve 51 to a reservoir 56 and to the right hand side of a fourth piston 55 of relay 44 integral with a fifth piston 56 operable to open arcing chamber 19 and motor 24 to atmosphere. Piston 55 is of smaller diameter than piston 43 and normally closes a set of contacts 57 connected in series with the contacts of an air relay 58 and controlling a holding circuit for coil 37. Air relay 58 is arranged to be responsive to the pressure within arcing chamber 19 and is provided with suitable means for delaying opening of the contacts thereof for a predetermined length of time after return of the pressure within arcing chamber 19 to atmospheric value.

Another air relay 59 similar to relay 58 controls the connections of coil 37 in response to the pressure in reservoir 54. The pistons of air relay 44 are normally maintained in the positions shown by means of a spring 60. Motor 18 may receive air under pressure from reservoir 12 through a magnet valve 61, the coil 62 of which may be connected with battery 36 through a push button switch 63. This connection preferably includes the contacts of an air relay 64 responsive to the air pressure in the cylinder of motor 17 to render the circuit breaker trip free.

Fig. 1 illustrates circuit breaker 6 in the normal operating condition thereof, contacts 7, 8 and 9, 10 being closed to complete circuit 11. Upon occurrence of an operating condition such as an overload or short circuit in circuit 11, resulting in an excessive flow of current therethrough, current transformer 33 supplies sufficient current to the coil of relay 34 to cause the relay contacts to close. A circuit is thereby completed from battery 36 through the contacts of relays 34 and 59, coil 37 and switch 39 back to the battery, and valve 38 is actuated to admit air from reservoir 12 to motor 24. Valve 23 is thereby opened to admit air from reservoir 12 into arcing chamber 19. After the pressure within arcing chamber 19 has built up to a sufficient value, valve 28 opens to admit air from arcing chamber 19 through valve 28 and slide valve 29 to the space adjacent the lower face of piston 27. Piston 27 rises and separates contact 7 from contact 8 against the action of spring 26. An arc is drawn between contacts 7 and 8 and is extinguished by the air blast escaping from chamber 19 through contact 7 and between plate 32 and slide valve 31. The flow of current through circuit 11 is interrupted and relay 34 returns to the position shown.

When piston 27 approaches the upper end of its stroke, a port 30 is uncovered thereby, through which air under pressure is admitted into the space below the lower face of slide valve 31. Slide valve 31 is raised into engagement with plate 32 to close the outlet from the arcing chamber. The space adjacent contacts 7 and 8 is accordingly filled with air at the pressure of reservoir 12 and the dielectric strength of this space is thereby raised to a sufficient value to preclude striking of another arc between contacts 7 and 8. Although pressure is then applied on both faces of piston 27, spring 26 cap-

not reclose contact 7 because valve 28 prevents return of air from the space below piston 27 to chamber 19.

During the above contact opening operation 5 and before return of relay 34 to the position shown, air is admitted from chamber 19 to relay 58 which thereupon connects coil 37 with battery 36 through a holding circuit independent of relay 34. Air is also admitted from arcing chamber 19 through relay 44 into reservoir 49 and under piston 52 of valve 51. After a predetermined time delay depending upon the capacity of reservoir 49, the pressure under piston 52 becomes sufficient to lift the piston, which opens 15 valve 51 and closes a port normally discharging reservoir 54 to atmosphere. Valve 51 admits air under pressure to relay 59 which is actuated thereby to cause relay 34 to thereafter control coil 42 instead of coil 37. Air pressure is also applied to the lower face of slide valve 29 to 20 actuate the slide valve to the upper position thereof. Slide valve 29 places the lower faces of piston 27 and of slide valve 31 in communication with atmosphere and also applies air pressure to the upper face of slide valve 31 to cause slide valve 31 to reopen. The contact opening action of piston 27 is terminated, and the decreasing air pressure on the upper face of piston 27 causes the piston to cooperate with spring 26 to return contact 7 to the position shown. Reclosing of contact 7 takes place after a predetermined time delay while valve 23 is still open as a result of the connection of valve 23 with valve 51 through arcing chamber 19 and reservoir 49 forming a pneumatic interlock therebetween.

The above described portion of the operation of the circuit breaker takes place regardless of whether or not the disturbance in circuit 11 has been terminated by opening of contacts 7, 8. 40 Upon reclosure of these contacts, three different sequences of operation may take place. Let it first be assumed that the disturbance was of transient nature, such as an arc to ground from an otherwise sound conductor of circuit 11 following a stroke of lightning and that the disturbance is terminated by opening of contacts 7, 8. Upon reclosure of contact 7 in the manner above described, the operation of circuit 11 is restored to its normal condition and relay 34 remains in the position shown.

After a predetermined time delay depending upon the capacity of reservoir 54, the pressure within this reservoir rises to a sufficient value to cause piston 55 to be displaced to the left against the action of spring 60. Contacts 57 open the holding circuit for coil 37, thus causing valve 38 to return to the position shown and to discharge the air previously admitted into motor 24. Valve 23 closes to disconnect arcing chamber 19 from reservoir 12. The air contained within the arcing chamber is discharged to atmosphere between pistons 55 and 56 of valve 44 which also assist in discharging the air from motor 24. Piston 56 also releases the air contained within reservoir 49. The pressure within reservoir 49 decreases and piston 52 of relay 51 is returned to the position shown, opening a port placing reservoir 54, relay 59 and slide valve 29 in communication with atmosphere. Relay 59 and slide valve 29 immediately return to the positions shown. Reservoir 54 gradually discharges to atmospheric pressure and permits piston 55 of relay 44 to return to position shown after a time delay. Relay 58 returns to the position shown after a time delay depending upon the adjustment thereof.

The system is then again in the normal operating condition thereof and is again ready to function as if contact 7 had not been opened. The above sequence of operations is represented by the chart Fig. 4a in which the different columns represent successive arbitrary intervals of time reading from left to right. The different members of the system are listed in a column at the left side of the chart and a circle in any column indicates that the element listed on the same line is displaced from the position shown. Elements which are always actuated together are listed on the same line to simplify the chart.

Let it next be assumed that the disturbance is of the type which is not removed upon opening of circuit breaker 6, such as a permanent short circuit resulting from rupture of a conductor of circuit 11. Upon reclosure of contact 7, as above described, the excessive flow of current through circuit 11 is immediately reestablished and relay 34 is again actuated in response thereto. Relay 34 connects battery 36 with coil 42 through the contacts of relay 59, which is then maintained in the depressed position under the control of the reclosing system of contact 7. The purpose of this connection is to render relay 34 operable during a predetermined period following reclosure of contact 7 to cause reclosure of valve 51 and opening of all the contacts of the circuit breaker. Coil 42 causes opening of valve 41 which admits air under pressure from reservoir 12 to the left side of piston 43 and to the space above piston 53. Valve 51 is thus reclosed and pistons 43, 45 and 46 are displaced to the right. Contacts 47 are closed to complete a holding circuit for coil 42 independently of relay 34. Piston 46 and valve 51 cooperate to discharge the air contained in relay 59 and below slide valve 29. The slide valve returns to the position shown, removes the pressure applied to the upper face of slide valve 31, and reestablishes the connection between piston 27 and chamber 19 through check valve 28.

At this moment coil 37 is still energized from battery 36 through contacts 57 and through the contacts of relay 58 so that valve 23 is still open and piston 27 may reopen contact 7 to again interrupt the flow of current through circuit 11. Slide valve 31 is again raised to close arcing chamber 19. At the same time, piston 45 admits air from arcing chamber 19 to motor 17 which opens contact 9 of the disconnecting switch, leaving circuit 11 permanently open at contacts 9, 10. Auxiliary switch 39 opens the circuit of the coils 37 and 42, causing valve 23 and piston 43 to return to the positions shown. Arcing chamber 19 is then still filled with air under pressure.

After a time delay, valve 51 opens and slide valve 29 is raised in the manner above described to cause slide valve 31 to drop, thereby releasing the air contained within arcing chamber 19 and causing contact 7 to reclose. Reservoir 49 discharges into the arcing chamber and when the pressure in the reservoir has decreased sufficiently, valve 51 returns to the position shown to discharge the air contained within reservoir 54. If desired, such action may be accelerated by dimensioning piston 46 to have a loose fit in relay 44 to permit some of the air contained in reservoirs 49 and 54 to leak through the piston clearance. Relay 58 finally returns to the position shown and the entire system is then returned to the position shown with the exception of contact 9. The entire sequence of operations in this case is diagrammatically represented by the chart Fig. 4b.

Let it finally be assumed that the disturbance

in circuit 11 has been removed by opening of contact 7 in the manner above set forth, but that the disturbance again becomes effective between the time of reclosure of contact 7 and the time 5 of return of relay 59 and of slide valve 29 to the positions shown at the end of a predetermined period following reclosure of contact 7. Valves 29, 41, 51 and 44 are then still under the direct control of relay 34. The operation of the system, 10 accordingly, remains the same as the operation resulting from the occurrence of a permanent short circuit as above described if piston 56 has not yet opened contacts 57 at the time of re-establishment of the disturbance. If piston 56 15 has already been displaced to the left, the piston is returned to the position shown by the extension of the shaft of piston 45 which is then moving to the right and the operation of the system is again completed as above described to cause 20 opening of all the contacts of the circuit breaker. If, however, relay 34 recloses the contacts thereof after relay 59 has already returned to the position shown, the operation of the circuit breaker will be reinitiated in the manner above described 25 as if contacts 7, 8 have not previously been opened.

After opening of contact 9 and removal of the fault in circuit 11, the circuit breaker may be closed manually by closing switch 63. This 30 switch connects coil 62 with battery 36 to cause opening of valve 61. This valve connects motor 18 with reservoir 12 and the motor thereupon closes contact 9.

The circuit breaker may also be opened manually by momentarily closing switch 48 to cause 35 actuation of valve 41. Valve 41 admits air from reservoir 12 to the left side of piston 43 which is displaced to the right with pistons 45 and 46 to close contacts 47. The latter complete a holding 40 circuit for coil 42 and also connect coil 37 with battery 36. Valve 38 opens and causes opening of valve 23 which admits air from reservoir 12 into arcing chamber 19. Contact 7 opens in the manner outlined above and interrupts any 45 current which may be flowing through circuit 11. At the same time piston 45 admits air from chamber 19 to motor 17 to cause opening of contact 9 and of auxiliary switch 39. The latter opens the circuit of coils 37 and 42 and causes 50 the circuit breaker, with the exception of contact 9, to return to the position shown. This operation is represented by the chart Fig. 4c.

In the embodiment illustrated in Fig. 2, circuit breaker 6 is assumed to be simplified by the 55 omission of slide valves 29 and 31 and of check valve 28. Contact 7 may then be reclosed by admission of air from reservoir 12 to the space above piston 27 through an air relay 66 similar to relay 44 but comprising a stepped piston 67 60 forming a valve integral with a second piston 68 and acting against another piston 69 through a spring 71. Piston 67 is controlled by a valve 72 provided with an actuating coil 73 and controls in turn a plurality of contacts 74, 75. Piston 69 is controlled by a valve 76 having an actuating 65 coil 77 and controls a plurality of contacts 78, 79.

Motor 17 is controlled by a second air relay 81 70 provided with a stepped piston 82 integral with another piston 83 and maintained in a neutral position by a pair of springs 84, 85. Movement of piston 82 is controlled by a valve 86 having a coil 87 and by a valve 88 having a coil 89. Piston 82 controls a plurality of contacts 91, 92 and 93. In the present embodiment, motor 24 of valve 23 also controls a plurality of contacts 75

94, 95. The different coils and contacts above described cooperate with a reclosing relay 96 provided with normally closed contacts 97, instantaneously closing contacts 98, and contacts 99 closing with a time delay. In particular, relay 96 forms an interlock between valves 23 and 67 to cause reclosure of contact 7 while valve 23 is still open. Opening operation of the circuit breaker may be controlled manually by means of a pushbutton switch 100. 10

The operation of circuit breaker 6 will be described following the same procedure as with respect to the embodiment illustrated in Fig. 1. Upon occurrence of any disturbance in circuit 11 resulting in an excessive flow of current therethrough, relay 34 closes the contacts thereof to connect coil 37 with battery 36 through contacts 97 of relay 96 and through auxiliary switch 39. Coil 37 opens valve 38 which in turn causes opening of valve 23 and actuation of contact 7. The flow of current through circuit 11 is thereby interrupted and relay 34 returns to the position shown. In addition to opening valve 23, motor 24 closes contacts 94 which complete a holding circuit for coil 37 through contacts 91 independently of relay 34 and also closes contacts 95 which connect the coil of relay 96 with battery 36. Relay 96 immediately opens contacts 97 and closes contacts 98 to prepare the system for a further step in the operation thereof. 20 25 30

After a predetermined time delay, relay 96 closes contacts 99 which connect coil 73 with battery 36 through contacts 78 and 93 and through switch 39. Valve 72 is thereby opened 35 and admits air from reservoir 12 to the left side of piston 67. The piston is displaced to the right and admits air under pressure from reservoir 12 to the upper face of piston 27 to cooperate with spring 26 in reclosing contact 7 against the action of the air from chamber 19 on the 40 lower face of piston 27. Piston 67 also closes contacts 75 which complete a holding circuit for the coil of relay 96 independently of contacts 95, and closes contacts 75 which connect coil 87 with battery 36. 45

Assuming first that opening of contact 7 has removed the disturbance from circuit 11, upon reclosure of contact 7 relay 34 remains in the position shown. Coil 87, which is then energized, opens valve 86 which admits air from reservoir 12 to the left side of piston 82. Piston 82 is displaced to the right, closes contacts 92 and opens contacts 91 to cause deenergization of coil 37. Valve 38 closes and causes reclosure of valve 23. The air contained within chamber 19 escapes 55 to atmosphere between contacts 7 and 8, which are not in gas tight engagement. Piston 82 also opens contacts 93 to deenergize coil 73. Valve 72 recloses and permits piston 67 to return to the position shown and to discharge the air entrapped above piston 27. The circuit of coil 87 is opened by contacts 75 to cause piston 82 to return to the position shown. Contacts 74 and 95 being open, relay 96 returns to the position shown and the entire system is returned to the normal operating condition thereof. The entire 60 65 70 75 80 85 90 95 operation is represented by the chart Fig. 5a.

Assuming next that opening of contact 7 has not removed the disturbance from circuit 11, upon reclosure of contact 7 relay 34 closes the 70 contacts thereof to connect battery 36 with coil 77 through contacts 98 of relay 96. Coil 77 opens valve 76 which admits air from reservoir 12 to the right hand side of piston 69. Piston 69 is displaced to the left to open contacts 78 and to 75

close contacts 79. Opening of contacts 78 causes deenergization of coil 73 which permits piston 67 to return to the position shown to discharge the air contained within the space above piston 5 27. This action is accelerated by mechanical action of piston 69 on the extension of the shaft of piston 67. Until return of piston 67 to the position shown, contacts 75 connect coil 87 with battery 36 to cause opening of valve 86. Piston 10 82 was accordingly displaced to the right to open contacts 91, but a circuit for coil 37 was then closed through the contacts of relay 34 and through contacts 92. Valve 23 is thus maintained open through the above operation.

15 When piston 67 returns to the position shown, arcing chamber 19 is still filled with compressed air which opens contact 7 and blows out the arc drawn between contacts 7 and 8. Piston 67 also opens contacts 75, and coil 87 is deenergized. 20 Valve 86 recloses to cause piston 82 to return to the position shown. Closure of contacts 79 by piston 69 energizes coil 89 which admits air from reservoir 12 to the right side of piston 83 to displace piston 82 towards the left. Piston 82 again 25 closes contacts 91 to hold coil 37 in circuit with battery 36 and also admits air from arcing chamber 19 to motor 17, which permanently opens contact 9 and auxiliary switch 39. All the control 30 circuits are then open at the auxiliary switch and the relays return to the positions shown. Valve 23 is reclosed by spring 25 and contact 7 is reclosed by spring 26. This entire operation is represented by chart Fig. 5b.

Assuming finally that the disturbance in circuit 11 again becomes effective between the time of opening of contacts 91 by piston 82 and the time of return of relay 96 to the position shown, the circuit of coil 37 is momentarily opened at contacts 81 and valve 23 may be reclosed. Upon 40 reclosure of contact 7, however, relay 34 again connects coil 37 with battery 36 through contacts 92, valve 23 opens again and the operation of the system is completed as above described.

The circuit breaker may be opened manually 45 by closing switch 100 to connect coils 37 and 77 with battery 38. Coil 37 actuates valve 38 and causes opening of valve 23. Air is admitted from reservoir 12 into arcing chamber 19 to open contact 7 and to interrupt any current which might be flowing through circuit 11. Coil 77 actuates 50 valve 76, which admits air from reservoir 12 to the right hand side of piston 69. The latter closes contacts 79 to energize coil 89. Valve 88 is actuated to admit air from reservoir 12 to the right hand side of piston 83, which displaces piston 82 55 and causes air to be admitted thereby from arcing chamber 19 to motor 17. Motor 17 opens contact 9 and also actuates switch 39 to cause the remainder of the system to return to the position shown in the manner outlined above. This 60 operation is represented by the chart Fig. 5c.

Although but two embodiments of the present invention have been illustrated and described, it will be apparent to those skilled in the art that 65 various changes and modifications may be made therein without departing from the spirit of the invention or from the scope of the appended claims.

It is claimed and desired to secure by Letters 70 Patent:

1. In combination, a polyphase electric circuit comprising a plurality of phase conductors, a circuit breaker comprising a plurality of pole portions in number equal to the number of said 75 phase conductors and each comprising cooperat-

ing arcing contacts and cooperating disconnecting contacts serially connected with said arcing contacts in a different one of the said phase conductors, means responsive to an operating condition of said circuit for opening said arcing contacts, time delay means responsive to initiation of the opening operation of said arcing contacts for causing said arcing contacts to reclose, and means responsive to a continuance or reoccurrence of said operating condition and controlled by said contact reclosing means for causing opening of all said contacts. 10

2. In combination, an electric circuit, a circuit breaker comprising cooperating arcing contacts and cooperating disconnecting contacts serially connected with said arcing contacts in said circuit, means continuously tending to maintain said arcing contacts closed, means responsive to an operating condition of said circuit for opening said arcing contacts against the action 15 of the first said means, means responsive to the initiation of the operation of said contact opening means for terminating the action of said contact opening means and cooperating with the first said means to cause said arcing contacts to 20 reclose, and means responsive to said operating condition during a predetermined period following reclosure of said arcing contacts to cause 25 opening of all said contacts.

3. In combination, an electric circuit, a circuit breaker comprising cooperating arcing contacts and cooperating disconnecting contacts serially connected with said arcing contacts in said circuit, means for causing opening of said arcing contacts comprising a source of fluid under pressure, contact separating means and a valve for connecting said source with said contact separating means, means responsive to an operating condition of said circuit for opening said valve to cause opening of said arc contacts, means for 30 causing opening of said disconnecting contacts comprising a second contact separating means and a second valve for connecting said source with said second contact separating means, and means comprising said operating condition responsive means and means controlled by the first 35 said valve to cause the second said valve to open after opening of said arcing contacts. 40

4. In combination, an electric circuit, a circuit breaker comprising cooperating arcing contacts and cooperating disconnecting contacts serially connected with said arcing contacts in said circuit, means for causing opening of said arcing contacts comprising a source of fluid under pressure, contact separating means and a 50 valve for connecting said source with said contact separating means, means responsive to an operating condition of said circuit for opening said valve to cause opening of said arcing contacts, means for causing reclosure of said arcing contacts comprising contact closing means and a second valve connected with said source, means responsive to initiation of opening operation of said arcing contacts for actuating the second 55 said valve to cause reclosure of said arcing contacts, means for causing opening of said disconnecting contacts comprising a second contact separating means and a third valve for connecting said source with said second contact separating means, and means responsive to said operating condition during a predetermined period following reclosure of said arcing contacts for causing opening of all said contacts. 60

5. In combination, an electric circuit, a circuit breaker comprising cooperating arcing contacts 70

and cooperating disconnecting contacts serially connected with said arcing contacts in said circuit, means for causing opening of said arcing contacts comprising a source of fluid under pressure, contact separating means and a valve for connecting said source with said contact separating means, means responsive to an operating condition of said circuit for opening said valve to cause opening of said arcing contacts, means 10 for causing reclosure of said arcing contacts comprising contact closing means and a second valve connected with said source, means responsive to initiation of said opening operation of said arcing contacts for actuating the second said valve to cause reclosure of said arcing contacts, means 15 for causing opening of said disconnecting contacts comprising a second contact separating means and a third valve for connecting said source with said second contact separating means, and means responsive to a continuance or reoccurrence of said operating condition and controlled by said contact reclosing means to cause opening of all said contacts.

6. In combination, an electric circuit, a circuit breaker comprising cooperating arcing contacts and cooperating disconnecting contacts serially connected with said arcing contacts in said circuit, means for causing opening of said arcing contacts comprising a source of fluid under pressure, contact separating means and a valve for connecting said source with said contact separating means, means responsive to an operating condition of said circuit for opening said valve to cause opening of said arcing contacts, means 25 for causing reclosure of said arcing contacts comprising contact closing means and a valve connected with said source, means responsive to initiation of said opening operation of said arcing contacts for actuating the second said valve to cause reclosure of said arcing contacts, means 30 for causing opening of said disconnecting contacts comprising a second contact separating means and a third valve for connecting said source with said second contact separating means, and means responsive to a continuance or reoccurrence of said operating condition for opening the said third valve to cause opening of said disconnecting contacts between an opening operation of said arcing contacts and the 35 following reclosing operation of said arcing contacts.

7. In combination, an electric circuit, a circuit breaker comprising cooperating arcing contacts and cooperating disconnecting contacts serially connected with said arcing contacts in said circuit, means for causing opening of said arcing contacts comprising a source of fluid under pressure, contact separating means and a valve for connecting said source with said contact separating means, means responsive to an operating 40

condition of said circuit for opening said valve to cause opening of said arcing contacts, means for causing reclosure of said arcing contacts comprising contact closing means and a second valve connected with said source, and an interlock between said valves to cause the second said valve to be actuated to cause reclosure of said arcing contacts while the first said valve is open. 5

8. In combination, an electric circuit, a circuit breaker comprising cooperating arcing contacts and cooperating disconnecting contacts serially connected with said arcing contacts in said circuit, means for causing opening of said arcing contacts comprising a source of fluid under pressure, contact separating means and a valve for connecting said source with said contact separating means, means responsive to an operating condition of said circuit for opening said valve to cause opening of said arcing contacts, means for causing reclosure of said arcing contacts comprising contact closing means and a second valve connected with said source, an interlock between said valves to cause the second said valve to be actuated to cause reclosure of said arcing contacts while the first said valve is open, means for causing opening of said disconnecting contacts comprising a second contact separating means and a third valve for connecting said source with said second contact separating means, and means responsive to said operating condition during a predetermined period following reclosure of said arcing contacts for causing opening of all said contacts. 10 15 20

9. In combination, an electric circuit, a circuit breaker comprising cooperating arcing contacts and cooperating disconnecting contacts serially connected with said arcing contacts in said circuit, means for causing opening of said arcing contacts comprising a source of fluid under pressure, contact separating means and a valve for connecting said source with said contact separating means, means responsive to an operating condition of said circuit for opening said valve to cause opening of said arcing contacts, means for causing reclosure of said arcing contacts comprising contact closing means and a second valve connected with said source, means responsive to initiation of opening operation of said arcing contacts for opening the second said valve to cause reclosure of said arcing contacts, means for causing opening of said disconnecting contacts comprising a second contact separating means and a third valve for connecting said source with said second contact separating means, and means controlled by said contact reclosing means and cooperating with said operating condition responsive means for reclosing the second said valve and for opening of the third said valve to cause opening of all said contacts. 30 35 40 45 50 55 60
